UNITED STATES PATENT OFFICE.

WILLIAM H. SMITH, OF REED CITY, MICHIGAN.

TEMPORARY BED-RAIL.

No. 890,461.

Specification of Letters Patent.

Patented June 9, 1908.

Application filed August 15, 1907. Serial No. 388,728.

To all whom it may concern:

Be it known that I, WILLIAM H. SMITH, a citizen of the United States, residing at Reed City, in the county of Osceola and State of 5 Michigan, have invented certain new and useful Improvements in Temporary Bed-Rails, of which the following is a specification.

My invention relates to improvements in 10 short rails or blocks for use to support the ends of bedsteads for exhibition purposes, when it is desired to show the pattern of the head and foot pieces of a bedstead with as little waste of room as possible, and its object is to provide a cheap, durable and 15 slightly rail that may be readily applied or removed when desired. I attain this object by the mechanism illustrated in the accompanying drawing in which.

20 Figure 1 is a side elevation of a pair of bed posts with my device attached. Fig. 2 is a top plan of the same, and Fig. 3 shows the device detached.

Similar letters refer to similar parts throughout the several views.

In the accompanying drawing, Figs. 1 and 2, A represents the post at the head of a bedstead, and A' represents the same at the foot of a bedstead, and E represents the lugs that 30 are secured to the posts to receive and support the side rails.

My device consists of two straps, B, pivoted at b and having apertures at the ends for the passage of the ends D' of the staples 35 D, as shown, and I prefer to use a short metal strap, as C, at each end of the device, so located that the ends of the staple D will pass through them and cause them to form a substantial bearing between the ends of the 40 straps B and the sides of the lugs E. To apply this device I place the staple D into the rail slot in the lugs E, as shown in Fig. 2, and then place the straps C upon the ends of the staple and the ends of the straps B outside of 45 the straps C and draw them snugly against the surface of the lugs E with the thumb screws d.

It will be readily seen that when the device has been adjusted to any style of lug it will 50 not be necessary to take it apart when plac-

ing it upon such lugs, as the thumb screws d may be loosened enough so that the staples D may be passed over the ends of the lugs without difficulty.

By using longer or shorter staples D the 55 strips B may be adjusted to any size or shape of lug, it being understood that the strips C must be fitted accordingly, and I prefer that the strips C be used though in an emergency the device will hold a bedstead to place without these plates, but I design to have a set of plates for every set of staples used, and to provide these temporary rails to fit every form of lugs.

The device may be successfully used without the use of the vertical strips C but not nearly as satisfactorily as with, hence I prefer that these strips be always used, though I desire to control the use of the device in either form, as the invention is practically 65 complete in either form.

To further add to the efficiency of the device, I place a fabric washer or packing C' between the strap C and the side of the lug E to avert the danger of marring the surface of 75 the lug by direct contact with the strap. I also, sometimes, upset the ends of the staple at D' so that the thumb screws d will not be likely to be lost.

Having thus fully described my invention, 80 what I claim as new, and desire to secure by Letters Patent of the United States, is:

1. The combination in a temporary bed rail of two metallic strips pivoted together at the center and having apertures through the 85 ends, and staples adjusted to pass the ends through the apertures in the ends of the strips, and thumb screws engaging the ends of the staples to secure them to place, substantially as and for the purpose set forth. 90

2. The combination in a temporary bed rail of two metal strips pivoted together at the center and having apertures through the ends, staples adapted to engage the lugs of a bedstead, and passing through the apertures 95 in the ends of the strips, and short strips acting as washers on the ends of the staples between the ends of the longitudinal strips and the lugs, and a fabric washer between the vertical strips and the sides of the lugs. 100

3. In combination with the lugs of a metal bedstead, two longitudinal strips having apertures in the ends, two vertical strips having corresponding apertures in their ends, 5 staples arranged to engage the lugs and the apertures through the strips, and thumb screws engaging the ends of the staples to clamp the strips solidly to the lugs, substan-

tially as shown and described, and for the purpose set forth.

Signed at Reed City Michigan August tenth 1907.

WILLIAM H. SMITH.
